United States Patent Office.

CHARLES R. OTIS, OF CHICAGO, ILLINOIS.

Letters Patent No. 96,949, dated November 16, 1869.

IMPROVEMENT IN SEAMS FOR TIN CANS.

The Schedule referred to in these Letters Patent and making part of the same.

To all whom it may concern:

Be it known that I, CHARLES R. OTIS, of Chicago, in the county of Cook, and in the State of Illinois, have invented certain new and useful Improvements in Seams for Tin Cans; and do hereby declare that the following is a full, clear, and exact description thereof, reference being had to the accompanying drawings, and to the letters of reference marked thereon, making a part of this specification.

The nature of my invention consists in the formation of the seam, for constructing tin cans of any desired size or shape.

In order to enable others skilled in the art to which my invention appertains, to make and use the same, I will now proceed to describe its construction and operation, referring to the annexed drawings, in which—

Figure 1 is a perspective of a square tin can, made with my improved seam, and

Figure 2 is part end view and part cross-section of the sides forming the can, showing the shape of the seam, and the manner of joining the sides together.

To form a square can, the sides A A are formed in the following manner:

One of the vertical edges, *a*, of each side, is bent over close to and parallel with the side, while the other vertical edge, *b*, is bent at right angles with the side. The edge *b*, of one side, is then soldered to the edge

a of the adjoining side, which can be done much easier and far better than any seam now in use.

The upper and lower edges of the sides A A are bent in the same manner as the vertical edge *a*.

The four edges of the top B are bent at right angles, and the top then inserted between the upper edges of the sides A A, and soldered together. The bottom of the can is attached in the same manner.

The seams of other than square cans are made in the same manner. The edges *b b*, instead of being bent at right angles with the sides, are bent at the same angles the sides are to be in relation with each other.

For round cans, the edges are, of course, bent rounded.

Having thus fully described my invention,

What I claim as new, and desire to secure by Letters Patent, is—

A seam for tin cans, formed by bending the edges, substantially in the manner herein shown and described.

In testimony that I claim the foregoing, I have hereunto set my hand, this 23d day of August, 1869.

CHAS. R. OTIS.
